A. F. KEFFLO

GRINDING ATTACHMENT FOR AUTOMATIC BUTTON MACHINES

Filed June 8, 1923

Inventor:

By Alexander Dowell, Attorney.

Patented Sept. 2, 1924.

1,507,382

UNITED STATES PATENT OFFICE.

ALBERT F. KEFFLO, OF MUSCATINE, IOWA.

GRINDING ATTACHMENT FOR AUTOMATIC BUTTON MACHINES.

Application filed June 8, 1923. Serial No. 644,267.

To all whom it may concern:

Be it known that I, ALBERT F. KEFFLO, a citizen of the United States, residing at Muscatine, in the county of Muscatine and State of Iowa, have invented certain new and useful Improvements in Grinding Attachments for Automatic Button Machines; and I hereby declare that the following is a full, clear, and exact description thereof, reference being had to the accompanying drawings, which form part of this specification.

This invention is a novel improvement in machines for facing buttons, particularly pearl buttons, and has especial reference to that type of machine in which the button blanks are carried in chucks, traveling in an endless series, and adapted to present the blanks successively to grinding and drilling devices. In particular the invention is an improvement upon the machine shown in my Patent #1,205,453, dated November 21st, 1916.

The present invention provides novel means whereby the button blanks may be ground or faced so as to have flat or convexed faces; and to enable machines of the character mentioned to be operated at higher speed; and as stated in my said patent these objects are accomplished by means of a novel attachment or improvement which in brief comprises a horizontally disposed grinding disk located adjacent one end of the orbital path of the chucks, and adapted to operate upon a plurality of blanks held in different chucks as the latter travel past and around the disk, said disk being located relative to the line of travel of the chucks that the blanks held in the chucks will be subjected to the action of the grinding disk for a sufficient time to insure the desired cutting or dressing of the faces of the blanks without overheating the same; and novel means are provided whereby the said grinding disk may be adjusted both vertically and laterally so as to operate properly upon blanks for any desired thickness and size of lines.

In such machines the chucks travel to and from the grinding disk at a rate of from forty-five to fifty per minute; but by arranging the disk adjacent to one end of the orbit of the chucks and substantially concentric with such end of the orbit, the chucks will move circumferentially of the disk for part of their travel and can be subjected to the ac-

tion thereof a sufficient time to enable the disk to properly face the blanks without undue heating thereof.

The present invention has particular reference to the novel means whereby the desired various adjustments can be made and the parts held in adjusted positions, by use of two eccentric sleeves, by which the grinding disk may be supported and maintained in any desired position, said sleeves being respectively independently adjustable rotatorily of the main shaft or center by any suitable means, preferably by manually operated worm gears. Further object of the invention is to provide novel means for lubricating the movable parts; and novel means for removing the dust.

I will explain the invention in detail, with reference to the accompanying drawings, to enable others skilled in the art to manufacture and use the same; and summarize in the claims the essential features and combinations of parts for which protection is desired.

In said drawings:

Fig. 1 is an enlarged vertical section through the novel button blank grinding or facing machine attachment applied to a machine of the type shown in my aforesaid patent.

Fig. 2 is a detail plan view of the gearing for adjusting the grinder.

Fig. 3 is a detail transverse section of the line 3—3 Fig. 1.

The machine to which my novel attachment is applied may be of any suitable kind, but is preferably one of the so-called "automatic button machines"; and as shown in my said patent has an endless series of connected chuck holders C, arranged to travel in an orbital path and operated by suitable means on preferably vertically disposed shafts journaled in the main frame. On one of said shafts adjacent one end of the path is usually mounted a body carrying a rotary series of drills adapted to operate upon the button blanks B held in chucks carried in the holders C; such drills operating upon the blanks B held in the chucks as they travel by and beneath the series of drills. Adjacent the other end of the orbital path of the chucks is a shaft A which usually carries tools for facing the blanks in the chucks as they move around the shaft. In applying my invention to such a machine I remove the devices heretofore employed on such ma-

chines for facing or grinding the blanks, and place on the shaft A a rotatable and slidable sleeve 1, which is adjustably supported upon the shaft A in any suitable manner, preferably as hereinafter explained. This sleeve 1 is bored eccentrically for the passage of the shaft A as indicated in Figs. 1 and 3. Supported on and surrounding this sleeve 1 is a second sleeve 2 which is eccentric to and 10 rotatable on the sleeve 1. These sleeves 1 and 2 are independently rotatably adjustable by any suitable means; and sleeve 1 can be turned independently of sleeve 2 relative to shaft A and sleeve 2; and sleeve 2 can be 15 turned independently of sleeve 1 relative to shaft A and sleeve 1.

In the construction shown the sleeve 2 is supported on a collar or flange 1^a on the lower end of sleeve 1; and the sleeve 1 is 20 longer than the sleeve 2. To the upper end of sleeve 2 is secured a worm gear 2^g which meshes with a worm 3^g on a shaft 3 which is journaled in bearings in depending lugs 15^g on opposed castings 15, which are disposed 25 on opposite sides of the shaft A and upper end of sleeve 1, and are fastened together by means of through bolts 15^a so that they together form a rigid bracket or head loosely surrounding the shaft A and the upper end 30 of sleeve 1.

On the upper end of sleeve 1, below the castings 15, is secured a worm gear 1^g meshing with a worm 4^g on a shaft 4 journaled in depending lugs on arms 15^h on 35 the castings 15 preferably opposite the arms 15^g. The shafts 3 and 4 are provided with hand wheels 3^a, 4^a, by which they can be manually rotated; by turning shaft 3 sleeve 2 can be turned on sleeve 1; and by turning shaft 4 sleeve 1 can be turned relatively to 40 the shaft and sleeve 2.

Rotatably mounted upon the sleeve 2 is a disk 5 preferably having an annular groove 5^a in its under side in which is secured a grinding ring or disk 6, of carbide or other suitable abrasive material, which ring projects below the lower face of the disk 5 and may be retained in place by any suitable means, as by an annular plate 5^b secured to the under side of the disk by screws 5^c. The disk 5 may be rotatably supported upon a flange or collar 2^c on the sleeve 2, as shown, and suitable anti-friction bearings may be used to support the disk 5 on the flange 2^c. To disk 5 is connected 55 a belt pulley 5^e which may be driven by a belt from a pulley on the driven shaft of the machine; as in my said patent so that the grinding disk may be rotated at the desired speed when the machine is in operation.

The grinding ring 6 is of such size and so located that it can simultaneously operate upon a number of blanks B held in the 60 chucks E as they move around shaft A.

The chucks may be elevated by the usual cam track as they come beneath the grinding disk as explained in my said patent, so that the ring 6 will properly operate upon and face each blank as it passes around the 70 disk, and while such blanks are moved around the abrasive disk by the chucks the blanks are also gradually fed upwardly toward the disk, by means of the guide or cam track upon which the chucks are supported as usual in this type of machine, and as explained in my said patent thus enabling the disk to gradually reduce the blanks to the desired thickness and surface contour, as they travel past the disk, as described in my said patent.

The diameter of the ring 6 is such that it will preferably coincide with or only be slightly eccentric to the arc or circle traversed by the chucks in passing around the shaft A, or to that portion of the orbital travel of the chucks concentric to the shaft A. The disk 6 rotates on an axis that is relatively stationary to the chucks, and the latter travel therewith; and thus a large 85 horizontally disposed abrasive disk or ring can simultaneously operate upon a number of blanks and can also operate upon each blank if desired during nearly 130 degrees of travel of the blank holding chucks 90 around the disk; and this enables the speed of the machine to be greatly accelerated, as compared with the speed of a machine having only the ordinary means for facing the blanks.

By adjusting either or both of the sleeves 1 and 2 the disk 6 can be adjusted laterally of shaft A; and can thus be adjusted eccentrically to the shaft A, and held in any desired position when adjusted, by means 105 of the aforesaid worm gearing, which prevents any backplay and holds both sleeves 1 and 2 fixedly in adjusted position relative to the shaft A and consequently relative to the travel of the chucks beneath the disk 6. 110 The grinding disk can be readily adjusted to compensate for wear of the grinding ring and to enable the disk to operate efficiently and properly upon any desired size or line of blanks.

The means for adjusting the disk by the worm gearing and eccentric sleeves is a very decided practical improvement upon the rocking or swinging adjustment of the disk shown in my aforesaid patent.

In the construction shown an oil cup 8 is attached to the lower end of the sleeve 2 and extends above the collar 2^c so that the bearing of the sleeve can be kept thoroughly lubricated at all times.

I also provide a dust hood or casing composed of an upper cylindric member 9 which loosely surrounds the hub or pulley 5^e above the disk 5 and is supported on the machine in any suitable way. This member 9 has 130

depending flange 9^a on its periphery which extends below the lower surface of the grinding disk 6. A bottom plate 9 is fastened to the flange 9^a and surrounds the shaft A below the cup 2^c and grinding disk 6; said bottom plate 9^c is slotted as at 9^c for the entry of the chuck ends and to permit the chucks to be lifted up sufficiently to engage the blanks with the grinding disk 6, which is enclosed in the hood as shown in Fig. 1.

The hood is preferably provided with a vent or outlet opening 9^f which may be connected by a pipe, not shown, to a suitable suction apparatus, not shown, whereby the dust produced by the grinding operations is withdrawn from the machine.

The hood 9 is preferably hung in any desired manner from arms 15^s extending radially from the casting 15, as shown in Figures 1 and 2, so as to support said hood 9 in proper relation to the grinding disk 6, the manner in which said hood is hung forming no part of the present invention.

25 The sleeves 1 and 2 and grinding disk 5 might be adjusted vertically by the means suggested in my aforesaid patent, but preferably instead of using that particular means I provide the upper end of sleeve 1 with a collar 1^b concentric to shaft A, and with an annular groove 1^c in the upper end of the sleeve below the collar 1^b. The collar 1^b is engaged in an annular recess 15^k in the castings 15, there being a flange 15ⁱ at the bottom of the recess which enters the groove 1^c and supports the flange 1^b.

Upon the shaft A above the sleeve 1 is a short sleeve 10 which has a flange 10^a on its lower end which engages the recess 15^k and underlies the flange 15^m at the top of the recess 15^k, whereby the castings 15 are hung upon the collar 10. This collar 10 may be slidably suspended on the shaft A by any suitable means as by a pin 10^e passed through a slot A² in shaft A and suspended by a rod 10^d passing through a central bore 10^e in the shaft A (such as described in my said patent) or by other means whereby the rod and collar may be readily vertically adjusted to raise and lower the sleeves 1 and 2 and parts carried thereby.

What I claim is:

1. In a button grinding machine the combination of a shaft, a rotatable sleeve eccentrically mounted on said shaft, a second sleeve eccentrically mounted on the first sleeve and a grinding disk rotatably positioned on the second sleeve.

2. In combination with mechanism as set forth in claim 1, means for adjusting the grinder longitudinally of the shaft.

3. In combination with mechanism as set forth in claim 1, means for independently adjusting the sleeves relatively to the shaft and to each other.

4. In combination with mechanism as set forth in claim 1, a worm gear on each sleeve and a worm fixed relatively to and engaging each gear, whereby each sleeve may be rotatorially adjusted independently of the other sleeve and shaft.

5. In combination with mechanism as set forth in claim 1, means for independently adjusting the sleeves relatively to the shaft and to each other and means for vertically adjusting the sleeves and grinder on the shaft.

6. In combination with mechanism as set forth in claim 1, a dust hood enclosing the grinding disk and provided with openings 80 for the presentation of the blanks by the chucks to the grinding disk and for withdrawing the dust from the hood.

7. In combination with mechanism as set forth in claim 1, a worm gear on each sleeve 85 and a worm fixed relatively to the gear for engaging the gear, whereby each sleeve may be rotatorially adjusted independently of the other sleeve and shaft, and means for vertically adjusting the sleeves and grinder on 90 the shaft.

8. In combination with mechanism as set forth in claim 1, a collar slidably mounted on the shaft above the sleeves, means suspending the collar, and means for rotatably 95 suspending the sleeves on said collar, substantially as described.

9. In combination with mechanism as set forth in claim 1, a bracket surrounding the shaft and having an annular recess engaging a flange on the sleeve, a collar on the shaft having a flange engaging a recess in the said bracket, and means for adjusting the collar on the shaft whereby the sleeves 100 are adjusted on the shaft therewith.

10. In combination a shaft, a sleeve, a bracket surrounding the shaft above the sleeve and having an annular recess engaging a flange on the sleeve, a collar on the shaft above the sleeve having a flange engaging a recess in the said bracket, and means for adjustably supporting the collar whereby the sleeve is rotatably suspended on the collar and adjusted therewith.

11. In combination with mechanism as set forth in claim 10, a second sleeve eccentrically mounted on the first mentioned sleeve, a grinder rotatably positioned on the second sleeve, and means for independently adjusting the sleeves relatively to the shaft and to each other.

12. In combination with mechanism as set forth in claim 10, a second sleeve eccentrically mounted on the first mentioned sleeve, a worm gear on each sleeve, and a worm engaging the gears, whereby each sleeve may be rotatorially adjusted independently of the other sleeve and shaft.

13. In combination with mechanism as set forth in claim 10, a second sleeve eccentrici-

cally mounted on the first mentioned sleeve, means for independently adjusting the sleeves relatively to the shaft and to each other, and means for vertically adjusting the sleeves on the shaft.

14. In combination with mechanism as set forth in claim 10, a second sleeve eccentrically mounted on the first mentioned sleeve, a worm gear on each sleeve and a worm relative to and engaging each gear whereby each sleeve may be rotatorially adjusted independently of the other sleeve and shaft;

and means for vertically adjusting the sleeves on the shaft.

15. In combination with mechanism as set forth in claim 10, a grinder rotatably mounted on said sleeve, a dust hood enclosing the grinder and provided with openings for the presentation of the blanks by the chucks to the grinder and for withdrawing the dust from the hood.

In testimony that I claim the foregoing as my own I affix my signature.

ALBERT F. KEFFLO.
